ATTORNEY.

UNITED STATES PATENT OFFICE.

WILLIAM J. HUMPHREY, OF CLEVELAND, OHIO.

IDENTIFICATION OR LAUNDRY TAG.

Application filed October 24, 1923. Serial No. 670,504.

To all whom it may concern:

Be it known that I, WILLIAM J. HUMPHREY, a citizen of the United States, residing at Cleveland, in the county of Cuyahoga and State of Ohio, have invented certain new and useful Improvements in Identification or Laundry Tags, of which the following is a specification.

This invention is an identification or laundry tag so constructed and bearing such indicia as to indicate to the operator the number of articles of laundry to be packaged together.

It is also an object to provide a tag bearing indicia identical to indicia placed upon a laundry slip so that an operator may positively determine the number of and the proper articles to be packaged together upon comparing the slip and tag.

20 A further object is to provide a tag of this character bearing a serial number and a character or characters thereabove, the characters and the last numeral of the serial number serving as a key to indicate the number of articles to be packaged together.

It is likewise an object to provide identification tags of this character arranged in sets and the sets being adapted for use upon articles to be packaged together.

30 Other objects will be in part obvious and in part pointed out hereinafter.

In order that the invention and its mode of operation may be readily understood to persons skilled in the art, I have in the accompanying illustrative drawings, and in the following detailed description based thereon set out one possible embodiment of the same.

In these drawings:

40 Fig. 1. is a perspective view of a portion of a strip of tags to be used where there is one article to a package.

Fig. 2. is a similar view showing the tags to be used where there are two articles to 45 a package.

Fig. 3. is a similar view of tags to be used where three or more articles are packaged together.

Fig. 4. shows edge and bottom plan views of a tag attached to an article.

Fig. 5. is a perspective view showing the detail construction of a tag, and

Fig. 6. is a detail perspective view showing the connection between the tags.

55 While these tags might be used in ordi-

nary laundries which handle the general run of washing, they are primarily designed for use in establishments specializing in laundering heavy articles, such as overalls and heavy shirts, etc. These articles 60 are almost invariably sent to the laundry in bundles varying in number. Often there are one or two suits of overalls to a bundle and other times there are a great number bundled together. When the time comes 65 to package the proper suits together for delivery to a certain shop it is difficult to properly sort them with assurance of the return to a shop or department of the same suits collected. Furthermore the work involves the necessity of considerably more labor than is required with the utilization 70 of my tag.

Having more particular reference to the drawings throughout which similar characters of reference designate similar parts, this improved tag may be stated broadly as comprising a body to be attached to an article and bearing markings whereby the worker may quickly determine the number 75 of articles constituting a completely assembled set for packaging together.

The usual laundry slips are employed with these tags and are each marked by the marker with the same number etc., that 80 the tag or tags carries or carry and by which proper sorting is attainable.

Where a package comes into a laundry containing one suit of overalls for instance, one of the tags shown in Fig. 1 is used, 90 this tag bearing a serial number as indicated at 7, said number ending with an odd numeral. Above the serial number is placed a single character A, B, or C, according to how high the numbers have run. The odd 95 numeral at the end of the serial number is the key by which the worker determines that there is only one one piece suit to be packaged and consequently does not need to make further search.

Where two one piece suits are to be placed together in a package for delivery to a shop or the like, tags as shown in Fig. 2 are used. These tags are arranged in identically marked pairs as shown in Figs. 2 and 6. 105 The serial number ends in an even numeral and together with a single characters arranged above it, indicates that two pieces are to go together.

Often there are three, four or even more 110

one piece suits to go in a single package in which event the tags shown in Fig. 3 are used, these being arranged in sets. All tags in each set are identically marked, bearing a serial number ending in an even numeral and having a pair of letters or characters arranged above. The marking on the tags together with the same marking on the slip and a number on the slip indicating definitely the number of suits to go with the slips positively eliminates liability of incorrect assembly of suits for wrapping or packaging and saves unnecessary labor. In other words where more than four pieces are to be delivered to one party, a number of tags corresponding to the number of pieces is employed, each tag bearing identical indicia arranged on the principle of that embodied in the illustration in Figure 3. Extra tags may be made up from blanks where the number of pieces outnumber the number of tags in any particular set. In all cases a laundry slip is included and bears indicia identical to that on the tags, and in addition, information as to the number of pieces to be packaged together. Through examination of the slip, the worker may determine whether there are more than four pieces and at the same time note the serial number, etc., by which he can identify pieces to be arranged together. Where four or a less number of pieces go together it is unnecessary to examine the slips to determine the number of pieces. This is not the case in the usual system. The combination of characters and serial number shown in Figure 3 may mean three, four, or more garments, it being necessary for the packer to examine the usual slip in order to determine the exact number of pieces bearing a particular tag.

The tags are arranged in strips and the dividing line between each tag is relatively thin to facilitate separation of the tags so I may fill in and enlarge certain sets where more than four pieces are together. I provide extra strips which are blank and adapted to be marked as circumstances demand, that is if I have five pieces I use the first

four tags from the tags in Fig. 3 and make a fourth similar tag from a blank.

Each tag comprises a face or body portion 8 having at opposite ends attaching fingers or feet 9 one of which is tapered for passing through the suit material, while the other takes over the edge of the material and the two clamped as shown in Fig. 4.

This tag may be readily attached by hand but is preferably attached by means of a special machine which accurately positions and secures the tags upon the garment.

Certain changes may be made in minor details of structure and arrangement, and such changes as may fall within the scope of the appended claims, I consider my invention.

I claim:

1. Means for identifying and designating the number of articles of clothing or the like to be packaged together, said means comprising sets of tags arranged in strips, similar serial numbers and characters on each tag of a set, and different serial numbers and characters on each set, the last numeral of the serial number and the character being the key to designate the articles.

2. Means for identifying and designating the number of articles of clothing or the like to be packaged together, said means comprising sets of tags arranged in strips, similar serial numbers and characters on each tag of a set, and different serial numbers and characters on each set, the last numeral of the serial number and the character being the key to designate the articles, and attaching spurs for the tags.

3. Means for identifying and designating the number of articles of clothing or the like to be packaged together, said means comprising sets of tags arranged in strips, a serial number and double character carried by each tag of a set and being identical throughout a particular set, the last numeral of the serial number being an even number and combinable with the double character as a key to designate the articles.

In testimony whereof, I affix my signature

WILLIAM J. HUMPHREY.
